UNITED STATES PATENT OFFICE.

ROSS J. ELLSWORTH, OF ELIZABETH, NEW JERSEY.

MATTRESS-WRAPPING MACHINE.

Application filed October 26, 1921. Serial No. 510,692.

To all whom it may concern:

Be it known that I, Ross J. ELLSWORTH, a citizen of the United States, and a resident of the city of Elizabeth, county of Union, 5 and State of New Jersey, have invented a new and useful Improvement in Mattress-Wrapping Machines, of which the following is a specification.

The object of my invention is to provide a 10 simple, efficient and durable machine for wrapping mattresses so that the same may be carefully and properly wrapped in a sanitary manner. This object is accomplished by my invention, two embodiments of which 15 are hereinafter more particularly set forth.

For a more detailed description of my invention, reference is to be had to the accompanying drawings, forming a part hereof, in which—

20 Figures 1 and 2 are sectional views of one embodiment of a hand machine embodying my invention.

Figure 3 is a plan view of a portion of the same, and

25 Figure 4 shows a detail of construction.

Figures 5 and 6 are sectional views of a machine using power, Figure 5 being taken on the line 5—5 of Figure 6.

Throughout the various views of the 30 drawings, similar reference characters designate similar parts.

In the machine shown in the first four views in the drawings of this case, a hand power machine is shown with a fixed table. 35 In the remaining views a power machine is employed with a movable table, as will appear below.

Referring to the first four figures, 1 indicates the machine with a table top 2 supported by any suitable legs 3. At one end of the machine are brackets 4 which carry a roll 5 of paper of a suitable kind which is first spread on the table top 2 and this paper is made long enough to fall over the end 40 of the table, as shown at 6. A mattress 7 is then placed on the paper 6 and allowed to rest thereon in a flat condition with one end near the vertical guides 8 and 9 and between the same. The guide 8 consists of 45 two uprights which are inwardly flanged so as to guide a roller 10 for a purpose which will appear below. The guide 9 has two parallel uprights which are not flanged, but which are united at their lower ends and 50 hinged by a hinge 11 to the lower edge of the table top 2. The guides 9 are on opposite

sides of a roller 12. The rollers 10 and 12 are connected by two parallel bars 13 and 14, the bar 13 being fixed to the roller 10 and the bar 14 being fixed to the roller 12, and the bar 14 is slidably mounted in a suitable socket attached to the roller 12. These two parts are separated by the thickness of the mattress 7.

The roller 10 is connected by an extension 55 with a handle 16 by means of which it may be turned.

When the mattress 7 is in place, over the bar 13 the bar 14 is placed over the same and runs laterally thereof and the guide 9 70 is allowed to swing on the hinge 11 and is held in place by the pin 17. It will be understood that this pin not only passes through the guides 9, but also through the fixed ears 18 which are secured to the said 75 table top 2. When the handle 16 is turned the rollers 10 and 12 are turned about their centers which are in the axis about which the bars 13 and 14 are turned. This axis will separate from the table top 2 as the roll 80 increases and the guides 8 and 9 cause this axis to rise properly. The handle 16 is turned until the mattress 7 is rolled a substantial amount and then the end of the paper 6 is placed over the same and the rolling is continued so that the mattress and paper are rolled together. When the mattress is nearly rolled a brush with glue thereon is run across the paper on top of the roll in a proper position so that when the mattress is completely rolled the fresh glue comes in contact with the paper beyond the end of the mattress 7 and free of the same. The paper is then cut and the pin 17 is removed and then the guide 9 is allowed to fall by 95 swinging on the hinge 11 and the roller 12 with its bar 14 is pulled out of the mattress. Immediately thereafter the mattress is removed by pulling the same off the bar 13. When the mattress is so pulled the edges 19 100 of the paper, which is wider than the mattress, are folded on the ends of the mattress and then the mattress is sealed by means of discs which are secured to these folded over ends so that the mattress is wrapped with a 105 good strong wrapping in a clean and sanitary manner. Thereafter more paper is pulled through and a new mattress is put on the table top 2 and the cycle of operations is repeated.

110
In the embodiment of my invention shown in Figures 5 and 6, the table top 2 is not

fixedly mounted, but is movably mounted as it is pivotally mounted on a pivot 20 which is so arranged that one end of the table is farther removed from the pivot than the other so as to over balance near the rolling part of the apparatus. To counter balance this, a spring 21 connects this table top 2 with the floor 22. The roller 5 and brackets 4 are the same as before and so is the paper end 6 which is brought over the end of the table remote from the roller 5. A mattress 7 rests on the table top 2 and has its end as shown, between the bars 13 and 14 which are the same as before except that the bar 13 is fixed in a hub 23 which is mounted to turn in a suitable bearing 24 which rests on the floor 22 and is driven by a suitable pulley 25 which is connected to any suitable source of power. The bar 14 is fixed in a roller 12 the same as before, except that the guide 19 is carried by the floor 22 instead of the table 2 so that the table can rise and fall without interfering with the guide. The end of the table 2 near the bars 13 and 14 is provided with a strap or other means 26 which prevents the table from rising too far and it also has a hook 27 suspended therefrom which is adapted to engage with an eye 28 secured to the floor 22 so that the table end 28 may be held in its lowered position, if so desired.

In this embodiment of my invention the operation of rolling the mattress is precisely the same as before, except that instead of

having the axis about which the bars 13 and 14 rotate rise from the table 2 as the mattress is rolled and one layer begins to mount on another, the table 2 is lowered while the axis of rotation of the bars 13 and 14 remains at the same level.

While I have shown and described two embodiments of my invention, it is obvious that it is not restricted thereto, but that it is broad enough to cover all structures that come within the scope of the annexed claims.

Having thus described my invention, what I claim is:

1. A mattress rolling machine composed of a table, means for gripping and rolling a mattress and means for permitting a separation of the table and mattress rolling means as the roll increases in size.

2. A mattress rolling machine composed of a table with means for delivering paper at one end and means for gripping and rolling a mattress at the other and means for permitting a separation of the mattress rolling means and table as the roll increases in size.

3. A mattress rolling machine composed of a table, rollers connected by bars for gripping and rolling a mattress, means for mounting said rollers and means for permitting a separation of the table and mattress rolling means as the roll increases in size.

In testimony whereof, I have hereunto set my hand this 7th day of October, 1921.

ROSS J. ELLSWORTH.
